Howson & Howson

UNITED STATES PATENT OFFICE.

LYNN B. CASE, OF HIGHLAND PARK, NEW JERSEY, ASSIGNOR TO JOHN WALDRON CORPORATION, OF NEW BRUNSWICK, NEW JERSEY, A CORPORATION OF NEW JERSEY.

POLE FOR FESTOON DRYING.

Application filed January 21, 1925. Serial No. 3,761.

The invention relates to poles for drying paper, cloth or other similar material. They are particularly applicable to driers of the festoon type in which a large number of uniformly spaced horizontal poles are moved by a chain, or other suitable means, along a runway or track, and the material to be dried is suspended on the poles in a long series of festoons. The driers may operate 10 in a closed heating chamber or in an open room.

According to common practice, wooden poles are used. These have a tendency to warp and twist under the action of the heat, thus reducing the efficiency of the drier and frequently wrinkling or otherwise damaging the goods.

The principal object of the present invention is to provide a metal pole which will 20 not be subject to the disadvantages mentioned, and which at the same time will avoid any contact of the metal against the material, such contact being objectionable in many cases. Other objects will be apparent from the following specification and claims.

In the drawing which shows the preferred embodiment of the invention,

Fig. 1 is a diagrammatic view of a drier 30 of the type to which the invention is applicable;

Fig. 2 is a broken perspective view of a pole embodying the invention;

Fig. 3 is a longitudinal sectional view of 35 the pole; and

Fig. 4 is a transverse sectional view of the pole.

Referring to the drawing, particularly Fig. 1, 1—1 represent a series of poles supported 40 on a guide or track 2. The poles are adapted to be moved along the track by any suitable means such as a chain, not shown. The material to be dried is carried by the poles 1—1 and hangs down in festoons as shown 45 at 3—3.

As shown in Figs. 2 to 4, the pole 1 comprises a metallic body 4, which is preferably hollow or tubular for the sake of lightness. Surrounding the body 4 is a cylindrical jacket 5 of any suitable heat insulating or non-metallic material. This jacket may consist of a fabric or of a loose or cellular fibrous material. I do not limit myself to any particular method of making the jacket

or of putting it in place. It is essential, 55 however, that the jacket fit the body tightly so as not to be easily displaced. Preferably, as shown, the jacket covers only that portion of the body which supports the material, leaving the metallic ends exposed and adapted to engage the guide or track.

When the metallic body is tubular, either with or without the jacket, I prefer to make the wall thin in order to reduce the weight to a minimum. Increased strength is required, however, at the ends, where the pole 65 engages the guides and the driving chains. I therefore provide plugs 6—6 in the ends, which support the thin walls and prevent denting or collapsing. 70

With a tubular metallic pole, used either with or without a jacket, it is desirable to provide for the circulation of air to the interior to assist in keeping the pole from overheating. I therefore provide the body 75 4 with a number of small holes 7, which are preferably uniformly distributed. When a jacket, such as 5, is used it is provided with holes 8 which register with the holes 7.

From the foregoing description it will be 80 clear that I have provided a pole which is free from the objections incident to wooden poles, which is light and strong, and which will not in any way injure the material being dried. A plain metallic pole, 85 properly constructed, can be used for some materials; but for most materials, a plain metallic pole would be seriously objectionable on account of the tendency of the metal to absorb heat and transfer it to the material. 90 This inherent objection to a plain metallic pole is overcome by my improved pole, wherein the heat-insulating jacket surrounds the metal. The jacket prevents the pole from absorbing heat from excessively hot 95 gases at any point, and it also prevents the pole from transmitting an undue amount of heat to the material.

I claim:

1. In a pole for festoon drying, the combination of a metallic body, and a heat insulating jacket of a cellular fibrous material surrounding the body, whereby exchange of heat to or from the metal is kept at a minimum. 100

2. In a pole for festoon drying, the combination of a metallic body of uniform diameter throughout, and a non-metallic heat 105

insulating jacket surrounding the body at the portions which engage the material to be dried, the said metallic body projecting beyond the jacket at each end, whereby it is adapted to engage a track or other supporting means.

3. In a pole for festoon drying, the combination of a tubular metallic body with a thin integral wall, and plugs in the ends 10 of the body to reinforce it at the points of engagement with a track or other supporting means.

4. In a pole for festoon drying, the combination of a tubular metallic body with a 15 thin integral wall, a non-metallic heat insulating jacket surrounding the body at the portions which engage the material to be dried, the said metallic body projecting beyond the jacket at each end whereby it is

adapted to engage a track or other supporting means, and plugs in the projecting end portions of the body for reinforcing it at the points of engagement with the said track or other supporting means.

5. In a pole for festoon drying, a tubular metallic body having small holes in the wall thereof permitting circulation of air to the interior.

6. In a pole for festoon drying, the combination of a tubular metallic body having small holes in the wall thereof, and a non-metallic jacket surrounding the body and having small holes therein registering with the holes in the body, the said holes permitting circulation of air to the interior of the 35 pole.
